SHIPPING CRATE

Joseph J. Henze, Detroit, Mich.

Application June 5, 1933, Serial No. 674,370

3 Claims. (Cl. 217—36)

The present invention pertains to a novel shipping box or crate, having special reference to that class of box or crate which is constructed of wood slats that are secured together and reinforced with wire.

The primary object of the present invention is to provide a shipping box or crate that may be constructed in any suitable size to accommodate various articles, the box or crate being reinforced by wire in a manner to render it rugged and capable of withstanding rough usage. The reinforcing wire is interlaced around and between the slats and frame members that form the box or crate in a novel manner, the object being to place the wire so that it does not project outwardly from the outermost surface of the box or crate in a manner to form a projection which might interfere with piling the boxes or crates one upon another or side by side, nor which might cause distortion or damage to the wire itself as a result of its being struck by boxes, crates or other articles.

With the above and other ends in view, the invention consists in the matters hereinafter set forth and more particularly pointed out in the appended claims, reference being had to the accompanying drawing, in which—

Figure 1 is a side elevation of the present box or crate;

Fig. 2 is an end elevation;

Fig. 3 is a fragmentary cross sectional view on the line 3—3 of Fig. 1;

Fig. 4 is a longitudinal cross sectional view taken on the line 4—4 of Fig. 2;

Fig. 5 is a cross sectional perspective view illustrative of the manner in which the wire member is received in the lower frame members of the box or crate, and

Fig. 6 illustrates a slightly modified manner of receiving one of the reinforcing wires.

Like characters of reference are employed throughout to designate corresponding parts.

The numeral 1 indicates the top side frame members, 2 the bottom side frame members, 3 the top end frame members, and 4 the bottom end frame members. The top frame members have their ends secured together by corner gussets 5 and the bottom frame members are secured together at their abutting ends by gussets 6. Sealed to the bottoms of the bottom frame members 4 to extend parallel to the frame members 2 are a plurality of spaced bars 7, the outside bars preferably being secured directly underneath the frame members 2. Arranged transversely relative to the bars 7 are a plurality of slats 8, the

ends of which are interposed between the frame members 2 and the bars 7 and which are secured in this position by nailing the same, the nails preferably being driven through the bars 7, through the ends of the slats 8 and into the side frame members 2.

The sides of the box or crate, between the top frame member 1 and the bottom frame member 2, is formed of a plurality of slats 9 which have their ends secured to corner posts 10 which are secured at the inside corners of the top frame members to join them to the bottom frame members in spaced relation as illustrated. The ends of the box or crate, between the frame members 3 and 4, have slats 11 similarly mounted with their ends secured to the upright corner posts 10.

In each case the slats 9 and 11 are secured to the corner posts 10 by means of staples 12 that pass through a sheet metal corner gusset 13, through the ends of the slats 9 and 11 and into the corner posts 10.

In order to reinforce the described construction, there are provided drilled holes 14 in the upper frame members 1, the holes being drilled from the bottom edge to extend upwardly therein in a vertical plane when the box or crate is in its normal position as illustrated in the drawing. From the inside surface of the frame members are drilled holes 15 that connect with the holes 14 and a reinforcing wire 16 has its upper end passed through the bores 14 and 15 to project into the box. The inner projecting end of the wire is bent over as at 17 and secured by a staple 18. The frame members are formed of heavier material than the slats and the holes 14 are arranged so that their inner edges are flush with the outside surface of the slats so that the wire 16 that projects downwardly from the holes rests against the outside surface of the slats.

The lower frame members 2 and the ends of the slats 8 are notched as at 19 and the bars 7 are notched as at 20, the latter notch 20 extending approximately half way through the bars vertically. The notches in each case are formed of a given depth so that the bottom of the same is directly in line with the outside surface of the slats 9 and the bars 7 are provided with drilled holes 21 that extend through the bars horizontally to connect with the notches 20.

Each wire 16 extends downwardly against the outer faces of the slats 9 and is received in the notches 19 and 20, the lowermost end of the same being passed through the drilled hole 21 and bent over against the adjacent face of the bar 7 as at 22 and secured in this position by a staple 23.

Secured at its upper end to the inner face of the rail member 1 by the staple 18 that secures the end of the wire 16 is a wire 24 so that it extends downwardly along the inner faces of the slats 9. 5 The wire 24 extends outwardly at each edge of each slat 9 and is twisted around the wire 16 as at 25 and is secured to the wire 16 beneath the lowermost slat 9 as at 26.

The two upper end frame members 3 are provided with vertically drilled holes 27 and 28, respectively extending upwardly in the frame member from the bottom edge thereof and in line with the outside faces of the slats 11. Holes 29 and 30 are drilled from the inside faces of the 15 frame members to connect with the holes 27 and 28 respectively. The two lower end frame members 4 are notched as at 31 and 32 respectively, the notches being formed so that their bottoms are in line with the outside faces of the slats 11. 20 A wire 33 has one end passed through the holes 27 and 29 and is bent over and secured to the adjacent inner face of the frame member 3 by a staple 34. It then extends downwardly across the outer faces of the slats 11, through the notch 31, across the bottom faces of the slats 8, through the notch 32, upwardly across the adjacent faces of the slats 11, through the holes 28 and 30 and is then bent over against the adjacent face of the frame member 3 and secured by a staple 35. A wire 36 has one end secured to the frame member 3 by the staple 34 and extends downwardly across the inner faces of the slats 11, across the upper faces of the slats 8, and upwardly across the slats 11 at the opposite end 35 of the box, the end of the wire being secured to the opposite frame member by the staple 35. The wire 36 extends outwardly between each pair of slats 8 and 11 and this outwardly extended portion is looped or twisted around the wire 33 as 40 at 37.

In this manner the slats and frame members, which are secured together at their abutting ends, are reinforced and more securely tied together at points intermediate their ends by the wires 16 and 24, and the wires 33 and 36 and the wires 16 and 33 which extend across the outside faces of the slats are received in the frame members in a manner whereby they do not project outwardly in a manner to strike objects when the box or crate is being moved and cause damage to other objects as well as distort and damage the wires themselves.

Fig. 6 illustrates the manner in which a hole 38 may be drilled substantially diagonally through the member 3 to accommodate the wire 33 in a single drilling operation instead of providing the two holes 27 and 29.

Although a specific embodiment of the present invention has been illustrated and described, it is to be understood that various alterations may be made within the scope of the appended claims without departing from the spirit of the invention; and such changes are contemplated.

What I claim is:—

1. A box or crate including a pair of end panels and a bottom panel, said end panels including top and bottom frame members, a plurality of slats of smaller cross section than said frame members, said frame members and slats being arranged to present a smooth interior, said upper frame members being provided with holes opening through the bottom and the inside surfaces thereof, a wire having its opposite ends passed through said holes and supported thereby so that the runs extending from said holes lie flush with the outer faces of said slats, said wire being looped around said bottom panel, means for securing the ends of said wire to the inside surfaces of said top frame members, and a lacing wire laced around said slats and around said first named wire. 80 85 90

2. A box or crate including a pair of side panels and a bottom panel, bars secured adjacent to the sides of said bottom panel, each of said side panels comprising a plurality of slats arranged between top and bottom frame members, said frame members being of heavier cross section than said slats and arranged relative to the latter so as to present a smooth interior, said top frame members being provided with holes opening through the bottom edge and inside surfaces thereof, said bottom frame members being provided with grooves in line with said holes, said bars having grooves in line with said first named grooves, said bars having bores extending from the grooves therein to the inside surfaces thereof, wires having their upper ends secured to the inside surfaces of said top frame members, extending through the holes therein, received in said grooves, extending through said bores and secured to the inside surfaces of said bars, and interlacing wires laced around said slats and around said first named wires. 95 100 105 110

3. A box or crate including a bottom panel and side and end panels including top and bottom frame members, bars secured adjacent to the sides of said bottom panel and extending parallel to said side panels, the top frame members in said end panels being provided with holes opening through the bottom edge and inside surfaces thereof, wires looped beneath said bottom panels and having opposite ends passing through holes in said top frame members, means for securing said ends to the inside surfaces of said top frame members, said side top frame members having holes opening through the bottom edge and inside surfaces thereof, said bars having bores extending through to the inside surfaces thereof, said side bottom frame members having grooves in line with said holes and bores, and wires passed through said holes, grooves and bores, means for securing one end of each of said last named wires to the inside surfaces of said side top frame members, and means for securing the other ends of said wires to the inside surfaces of said bars. 115 120 125 130 135 140 145

JOSEPH J. HENZE.
